UNITED STATES PATENT OFFICE.

CHARLES H. JENKINS, OF BELLEVILLE, NEW JERSEY, ASSIGNOR TO NEWMAN CLOCK COMPANY, OF NEW YORK, N. Y., A CORPORATION OF NEW YORK.

KEY-CABINET FOR WATCHMEN'S TIME-REGISTERING SYSTEMS.

1,126,019.

Specification of Letters Patent.

Patented Jan. 26, 1915.

Application filed July 14, 1911. Serial No. 638,447.

To all whom it may concern:

Be it known that I, CHARLES H. JENKINS, a citizen of the United States, residing at Belleville, county of Essex, and State of New Jersey, have invented certain new and useful Improvements in Key-Cabinets for Watchmen's Time-Registering Systems, of which the following is a full, clear, and exact description.

10 This invention relates to watchmen's time-registering systems of the type in which each "station" visited by the watchman in his rounds is equipped with a key adapted when inserted in the register-clock 15 to cause a time imprint to be made on a record sheet in the clock. This clock the watchman carries with him, and at each station inserts the key belonging thereto to record the time of his visit to the station, so 20 that at the end of his tour of duty the time-imprints on the record sheet will show at a glance whether or not all the stations were visited and the time at which they were reached.

25 The present invention relates more particularly to the receptacles or cabinets located at the stations for holding the keys belonging thereto, and its chief object is to provide an improved cabinet of slight and 30 unobtrusive appearance for use in hotels and other buildings where the appearance of an object is of importance as well as its utility.

35 A further object is to provide a cabinet, particularly for use in hotels, of such character as to diminish as much as possible the noise incident to taking out and replacing the key.

40 To these and other ends the invention consists in the novel features of construction and combinations of elements herein-after described.

45 The preferred embodiment of the invention is illustrated in the accompanying drawing, in which—

Figure 1 is a longitudinal section showing the cabinet closed and the key in place. This figure also shows in dotted lines the cabinet open to afford access to the key.

50 Fig. 2 is a horizontal section on line II—II. The device comprises generally a metallic casing or framework 10, preferably of rectangular form, sunk in the wall 11 and having its front closed by a wall plate 12 resting against the wall around the opening

which receives the casing. At the top the front plate is provided with a pair of spaced lugs 13, between which the upper edge of the casing fits, as shown. On the top of the casing is a lug 14 having a threaded bore 50 to receive a clamping screw 15 extending rearwardly through the front plate 12. On the inside of the casing at the bottom is a similar lug 16 to receive the lower clamping screw 17. By setting up these screws 65 the front plate may be bound firmly to the casing and brought into close contact with the surface of the wall.

In the cover plate 12 is a central rectangular opening, and at the bottom of the 70 opening is a pair of inwardly extending lugs 18 to which are pivotally connected two arms 19 extending downwardly and forwardly from a horizontal base plate 20. On the front of this base plate and securely 75 fastened thereto in any convenient way is a closure or door 21 having its edge rabbeted as at 22 to fit closely the edge of the opening in the front plate 12. The front plate and the downwardly swinging door are prefer- 80 ably made of brass, polished or otherwise embellished to afford a pleasing appearance. At the top of the door is a rotary latch 23 to engage the edge of opening in the front plate 12 and so lock the door in closed position. A knob 24 is provided on the door to operate the latch.

The receptacle for the registering key 25 is in the form of a rectangular block 26, composed in whole or in part of non-acoustic 90 material as for example soft wood, provided with a deep cylindrical bore 27 to receive the key. This receptacle is mounted between and secured to lugs 28 on the door 21. The bottom of the bore or chamber is lined with 95 a sheet 29 of cloth, leather, soft rubber or the like, to deaden the sound as the key is tossed into the receptacle.

The registering key is fastened to one end of a retaining chain 30, the other end of 100 which passes through a hole in the base plate 20. Two pieces of coil spring 31, wormed onto the terminal link of the chain, fasten the same to the base plate.

Fastened by one end to the base plate are 105 two U-shaped springs 32, the other ends of which are looped as shown and bear on the bottom of the casing 10.

When the watchman unlatches the cabinet by turning the knob 24 the springs 32 throw 110

the door outwardly and downwardly, and with it the key receptacle 26, bringing the latter into easy reach. Removing the key the watchman inserts it in the clock, and 5 having made the desired registration replaces the key and closes the cabinet. The receptacle being made of or lined with non-acoustic material the replacement of the key can cause but slight noise at most, in no case 10 sufficient to disturb persons sleeping in nearby rooms. A latch which must be turned by hand to lock and unlock the cabinet is preferred to a spring or self-acting latch, as the latter might encourage slamming of the 15 door in closing it. The front or face plate 12 and door 21, the only parts exposed to view, can be made as ornamental as desired, and being practically flush with the wall are not at all obtrusive in appearance.

20 As before stated, the construction herein specifically shown and described is merely the preferred embodiment of the invention. The same can be embodied in various other forms without departure from its proper 25 spirit and scope as defined by the appended claims.

I claim:

1. A key cabinet for watchmen's time registering systems, comprising, in combination, 30 a casing adapted to be embedded in a wall and having its outer side open, a lug on the outside of the upper part of the casing having a screw threaded bore, a lug on the inside of the lower part of the casing having a 35 screw threaded bore, a plate arranged over the said open side of the casing having screw holes at either end thereof, clamping screws extending through the holes in the plate into said lugs to clamp the plate securely to the casing, an opening in said

plate, an outwardly opening closure hinged to the said closure at the bottom of the said opening, a vertical key receptacle mounted on the inner side of the said closure, and a substantially U-shaped spring member, having one arm secured to the key receptacle and the other resting against and movable upon the bottom of the casing to cause the casing to open. 45

2. A key cabinet for watchmen's time registering systems, comprising, in combination, a casing adapted to be fully embedded in a wall and having its outer side open, lugs on the upper and lower sides of the casing and having horizontal bores therein, a plate 50 adapted to lie over the open side of the casing and having perforations near its ends in alignment with the bores in the said lugs, means passing through the bores in the cover plate and lugs to secure the cover plate upon the casing, a rectangularly shaped opening in said cover plate, a closure for said opening, a vertical key receptacle mounted on the inner side of the said closure, means on said closure for locking the closure to the 55 cover plate, and a substantially U-shaped spring member located between the bottom of the casing and the vertical key receptacle, and having one of its arms secured to said key receptacle and the other resting against 60 and sliding upon the bottom of the casing, for opening the closure when the same is unlocked. 65

In testimony whereof I affix my signature in the presence of two subscribing witnesses. 70
